UNITED STATES PATENT OFFICE

2,005,443

HARMONICA

Walter R. Steele, Lemon Grove, Calif.

Application March 14, 1934, Serial No. 715,407

4 Claims. (Cl. 84—377)

My invention relates to improvements in harmonicas and the main object is to provide a chromatic harmonica having a range of three full octaves and by which any note in the common 5 or key of C scale may be played either a half tone higher or a half tone lower without changing the breathing action or the "hole" through which the breath is forced.

Another object is to provide a chromatic harmonica as above including three reed plates arranged on two notched sticks or frame members to which air is admitted through an apertured valve plate under control of a notched sliding valve in such manner that a reed on any reed 15 plate may be sounded by manipulation of the sliding valve to open the proper aperture in the valve plate, all without moving the mouth over the harmonica or changing the breathing.

Another object is to provide a novel, convenient and practical sliding valve and operating means in which said valve is normally held in position to admit air to the common scale reeds but may be moved to admit air to either the sharp or flat reeds by manipulation of a small 25 finger lever conveniently located at the end of the harmonica.

Another object is to provide a chromatic harmonica having a novel arrangement of reed plates and "sticks" or frame members by which 30 the maximum vibrating space is provided for the reeds without undue bulk in the harmonica, this being carried out by arranging the sticks in a V-shape meeting at their forward notched edges and diverging toward their rear edges with one 35 reed plate placed on top of the upper stick and the other two on top and on the bottom of the lower stick. The upper stick is notched out to leave a baffle shield between its notches and the lower stick and the notches in the lower stick 40 are just half the width of those in the upper stick whereby each reed is isolated from the next.

A further object is to provide a harmonica of this kind in a simple, practical and inexpensive form.

With these and other objects and advantages in view the invention resides in the novel construction and arrangement of parts as hereininafter fully set forth and claimed, reference being had to the accompanying drawing wherein:

Figure 1 is a front elevation of my harmonica.

Figure 2 is an enlarged cross section along the line 2—2 in Figure 1.

Figure 3 is a front elevation of the two sticks and reed plates alone.

Figure 4 is a front elevation of the valve plate.

Figure 5 is a front elevation of the sliding valve.

Figure 6 is a plan view partially broken away and in section.

Figure 7 is an enlarged fragmentary plan view 5 also partially broken away and in section showing the valve operating finger lever.

Referring now with more particularity to the drawing and in carrying out my invention I provide a V-shaped frame made up of a pair of 10 elongated rectangular wooden "sticks" or frame members 1 and 2 arranged one above the other with their forward margins 3 meeting and their rear margins 4 spaced apart resulting in what might be termed a V formation as shown. These 15 sticks are of any desired length according to the range of the instrument and are held in the relationship shown by small support studs 5. The upper stick 1 has a plurality of spaced recesses or cells 6 out in its forward margin and opening 20 therethrough and these recesses also open through the upper face of the stick but do not penetrate the lower face thus leaving thin baffle shields 7 intervening. The lower stick 2 has a pair of separate notches 8 and 9 in its forward 25 edge in alignment with and below each upper cell 6, these notches 8 and 9 being therefore considerably narrower than said recesses and opening through both the upper and lower faces and the forward edge of the stick. An upper reed plate 30 10 is secured to the upper face of the upper stick with a pair of reeds 11 over each cell 6. A center reed plate 12 is mounted on the upper face of the lower stick 2 with a reed 13 over each notch 8 and 9 and a lower reed plate 14 is mounted on the 35 lower face of the lower stick also with a reed 15 in line with each notch 8 and 9. The reeds of the upper plate 10 are tuned to the key of C natural while the reeds 13 and 15 on the center and lower plates which register with notches 8 40 are tuned to B natural or one half tone lower and the reeds on these plates which register with the notches 9 are tuned to the key of C sharp or one half tone higher. Guard plates or covers 16 are secured by screws or tacks 17 on 45 the exposed upper and lower faces of the sticks to protect the reeds in usual manner and the arrangement is preferably such that the free vibrating ends of the upper and lower reeds are turned forwardly and those of the center plate 50 turned rearwardly, this giving the maximum vibrating space for the reeds as shown without increasing the bulk or size of the instrument.

The frontal margins of the sticks are cut off 55 flush and straight as shown to receive a flat rec-

tangular valve plate 18 of thin sheet metal which is secured flat against these edges and has upper apertures or ports 19 registering medially with the upper recesses 6 and spaced pairs of lower apertures or ports 20 and 21 registering each with one of the lower notches 8 and 9. These ports 19, 20 and 21 are preferably small and rectangular in shape as shown. A rectangular flat sliding valve 22 also of thin sheet metal is placed over the valve plate 18 and has aligned notches 23 and 24 along its upper and lower edges the spacing between which is equal to that of the upper ports 19 in said valve plate. A trough-like mouth piece 25 is placed over the valve plate and sliding valve, being secured in place at its ends by small tacks or screws 26 which pass loosely through longitudinal slots 27 in the sliding valve and through apertures 28 in the valve plate into the upper stick 1. The ends 29 of said mouth piece 25 are formed or turned inwardly against the valve assembly and the right end is notched out at 30 to clear the end 31 of the sliding valve 22 which is thus exposed as shown. The mouth piece has air openings 32 aligned with the notches 23 and 24 in the sliding valve to admit air to the instrument as will be evident but no partitions are provided to direct the air to any particular opening. A mounting plate 33 is secured to the right end of the instrument by tacks 34 and has a medial ear 35 to which a finger lever 36 is fulcrumed medially at 37. One end 38 of said lever is reduced and rounded and passes through an aperture 39 in the exposed end 31 of the sliding valve 22 outwardly of which the valve is reduced and upset to form a knob 40. The other end of the lever has a similar knob 41 and by pressing either of these knobs 40 or 41 it will be evident that the lever will be swung back and forth on the ear 35 and the sliding valve 22 will be moved endwise to and fro across the valve plate 18. Inwardly of the mounting plate 33 a recess 42 is provided in the end of the instrument and spring pins 43 are passed slidably through the plate out into engagement with the finger lever 36 near its ends. Inwardly of said plate the pins 43 have diametrically enlarged heads 44 to limit their outward movement to the point that the lever will rest in a medial position as shown. A leaf or bow spring 45 is held at its center by a cross pin 46 through the recess 42 and bears at its ends against the heads 44 of the pins normally urging the pins outwardly to hold the lever in its medial position and returning it to that position after each operation.

The instrument is played in substantially the usual manner and in the rendition of any selection should tones one half tone higher or lower be desired, the finger lever 36 is operated by the fingers sliding the valve 22 across the valve plate 18 and bringing its lower notches 24 into registry with either of the series of ports 20 and 21. Thus when the valve is moved to the left the notches 24 register with the ports 20 admitting air to notches 8 in the lower stick 2 and sounding the reeds on the center and lower reed plates 12 and 14 which, as aforesaid, are tuned to B natural. Movement of the valve to the right then cuts off this alignment and opens the passage through notches 24, ports 21 and notches 9 to the center and lower reed plates 12 and 14 sounding the C sharp reeds thereon. Releasing the finger lever restores the notches 23 to registry with the upper ports 19 admitting air to the C natural upper reed plate 10. It is apparent that this action of the sliding valve is readily carried out without interfering with the

playing of the instrument. Of course the two reeds on the plates 12 and 14 registering with each notch 8 and 9 are separately operated, or sounded, one by "blowing" and the other by "drawing", these terms referring to the breathing.

It is understood that in accordance with the conventional construction of the reeds and reed plates of these instruments there are a pair of reeds registering with each cell and notch, one reed sounded by blowing through the instrument and the other by drawing through the instrument. These two reeds are tuned to adjacent tones or notes in the musical scale. The two reeds on the center and lower plates 12 and 14 adjacent each of the notches 8 and 9 will thus be tuned a half tone lower or higher than the corresponding reeds above on the upper reed plate 10 so that the natural tone sounded by blowing through the instrument may be sounded also a half tone lower or higher without changing the breathing and by proper manipulation of the sliding valve. In other words, by blowing through the instrument any alternate tone or its sharp or flat may be sounded and by drawing the breath through the instrument the adjacent tones may be sounded either natural or its sharp or flat tones.

It is thought that further details of the utility and advantages of the instrument will be apparent to those skilled in the art without further description.

While I have herein set forth a certain preferred embodiment of my invention, it is understood that I may vary from the same in minor structural details, so as best to construct a practical device for the purpose intended, not departing from the spirit of the invention and within the scope of the appended claims.

I claim:

1. In a device of the kind described, a frame comprising a pair of sticks meeting at their forward edges and diverging toward their rear edges, the uppermost stick having cells cut in its forward margin and opening through its upper side, the lower stick having a pair of notches cut in its forward edge below each cell in the upper stick, an upper reed plate secured on the upper stick over the cells therein, a center reed plate secured on the lower stick above the notches, and a lower reed plate secured on the underside of the lower stick below the notches, the said center and lower reed plates having their reeds communicating with the notches in the lower stick, and valve means for admitting air to any of the reed plates.

2. In a device of the kind described, a frame comprising a pair of sticks meeting at their forward edges and diverging toward their rear edges, the uppermost stick having cells cut in its forward margin and opening through its upper side, the lower stick having a pair of notches cut in its forward edge below each cell in the upper stick, an upper reed plate secured on the upper stick over the cells therein, a center reed plate secured on the lower stick above the notches, and a lower reed plate secured on the underside of the lower stick below the notches, the said center and lower reed plates having their reeds communicating with the notches in the lower stick, a flat valve plate mounted over the forward edges of the sticks and having ports registering with the cells and notches therein, a flat sliding valve slidably mounted over the valve plate and having spaced notches in its upper and lower edges adapted for selective registry with any of the ports on the valve plate.

3. In a device of the kind described, a frame comprising a pair of sticks meeting at their forward edges and diverging toward their rear edges, the uppermost stick having cells cut in its forward margin and opening through its upper side, the lower stick having a pair of notches cut in its forward edge below each cell in the upper stick, an upper reed plate secured on the upper stick over the cells therein, a center reed plate secured on the lower stick above the notches, and a lower reed plate secured on the underside of the lower stick below the notches, the said center and lower reed plates having their reeds communicating with the notches in the lower stick, a flat valve plate mounted over the forward edges of the sticks and having ports registering with the cells and notches therein, a flat sliding valve slidably mounted over the valve plate and having spaced notches in its upper and

lower edges adapted for selective registry with any of the ports on the valve plate and a finger lever fulcrumed at one end of the harmonica and connected at one end to the sliding valve, the said lever being spring set to normally hold the sliding valve in position to admit air to the cells and upper reed plate.

5

4. In a device of the kind described, a frame comprising a pair of sticks meeting at their forward edges, a troughlike apertured mouthpiece enclosing the frontal edge of the frame, the said sticks being notched at their frontal edges, a reed plate mounted on the upper sides of each of the sticks and one plate mounted below the said lower stick, and the said sticks diverging toward their rear ends whereby space is provided for the upper reed plate on the lower stick.
